UNITED STATES PATENT OFFICE.

ALLEN H. KERNGOOD, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND.

SUSPENDER BUCKLE.

1,425,778.

Specification of Letters Patent. Patented Aug. 15, 1922.

Application filed January 5, 1922. Serial No. 527,091.

To all whom it may concern:

Be it known that I, ALLEN H. KERNGOOD, a citizen of the United States, residing at Baltimore city, State of Maryland, have invented certain new and useful Improvements in 5 Suspender Buckles, of which the following is a specification.

This invention relates to buckles designed more particularly for adjusting the length of 10 suspenders and other garment supporters, straps, and the like, and it is the object of the invention to provide a novel and improved buckle of simple and inexpensive construction having certain advantages to be 15 pointed out in the detailed description appearing hereinafter.

In order that the invention may be better understood, reference is had to the accompanying drawing forming a part of this 20 specification, and in said drawing—

Figure 1 is an elevation of the buckle and a fragment of the part to which it is applied; Fig. 2 is an edge view thereof; Fig. 3 is a cross section on the line 3—3 of Fig. 1; 25 Fig. 4 is a perspective view of the buckle detached, and Figs. 5 and 6 are views similar to Figs. 3 and 4 showing a modification.

Referring specifically to the drawing, the buckle consists of a base plate 5 having outer- 30 standing side flanges or ears 6 to which latter are hinged two clamping levers 7 and 8 having gripping jaws, the jaws of lever 7 being shown at 7^a and the jaws of lever 8 at 8^a. The gripping jaws may be serrated as shown 35 to obtain a firm grip on the parts to be held.

The clamping levers 7 and 8 are located opposite one and the same face of the plate 5, and they are of such length that they may be positioned between the side flanges 6. 40 Each lever has side pins or studs which seat in apertures in the flanges 6 and form the hinge or pivot of the lever. The pivot studs of lever 7 are shown at 7^b, and those of lever 8 are shown at 8^b.

In applying the buckle to one of the shoulder straps 10 of a pair of suspenders, said strap is passed along the face of the plate 5 opposite which the lever 7 is located, so as to lie between this face of the plate and the jaw portion 7^a of lever 7, and upon swinging said lever in the direction of the plate, its jaw portion engages the strap and jams it against the plate, thereby causing the strap to be firmly gripped and held. Beyond the buckle, the 50 strap is looped and its end is placed between the plate 5 and the jaw portion 8^a of lever 55

8, and upon swinging said lever toward the plate, its jaw portion engages the strap end and jams it against the plate, whereby it is securely gripped and held. When the lever 7 is in strap holding position it overlaps the lever 8, and hence it is necessary to operate said lever 8 before the lever 7 is swung to strap gripping position. When both levers have been placed in strap clamping position, 60 the portion of the strap held by lever 7 covers the lever 8, and lever 7 lies against the outer face of said strap portion. The strap end, and the lever 8 holding the same are therefore completely covered, and hence said 70 lever cannot get caught on anything to become accidentally disengaged to release the strap end. The plate 5 has an aperture 11 which is opposite the free end of the lever 8 so that a rod, pin or the like may be inserted 75 through said aperture to engage the lever and swing it back to release the strap end.

The buckle will be found especially useful in connection with suspenders for adjusting the length of the shoulder straps thereof. It 80 will not be necessary to manufacture the straps in different lengths as is the customary practice, but they can all be made of the same maximum length, and adjusted by the wearer to obtain the desired length, in addition to the adjustment of the length of the looped portion of the straps. Thus, if the shoulder straps are too long for a person of a certain build and require an adjustment of the looped portion of the straps which would 90 locate the buckles too high on the person for comfortable wear, portions of the straps held by the lever 8 can be cut off, which would locate the buckles lower down on the person. This can be readily done as the strap end is 95 not permanently attached to the buckle by sewing it thereto as usual, but is detachably held by the lever 8, this being also a saving in the cost of manufacture of the suspenders.

In the modified structure shown in Figs. 5 and 6, the jaws of the clamping levers 7 and 8 are not serrated, and the ends of the base plate 5 are provided with lateral flanges 12. The jaws 7^a and 8^a are so located relative to these flanges that when said jaws are in 105 gripping position they are behind and close to the flanges, so that the strap portions are jammed therebetween, as clearly shown in Fig 5, whereby the hold on said strap portions is materially increased.

I claim:

1. A buckle comprising a base plate, and

a pair of clamping levers opposite one and the same face of the plate, and having jaws movable toward and from said face, one of the levers overlapping the other lever, and 5 the base plate having an aperture through which the free end of the last-mentioned lever is exposed.

2. A buckle comprising a base plate, and a pair of clamping levers opposite one and

the same face of the plate, and having jaws 10 movable toward and from said face, said levers being foldable one over the other when swung to clamping position, and the base plate having an aperture through which is exposed the free end of the lever which is 15 beneath the other lever.

In testimony whereof I affix my signature.

ALLEN H. KERNGOOD.
